CLAIM

The ornamental design for an adhesive bandage dispenser in the shape of a shoe, as shown and described.

DESCRIPTION

FIG. 1 is an isometric view of an adhesive bandage dispenser showing a first embodiment of my new design;

FIG. 2 is a right side view thereof;

FIG. 3 is a left side view thereof;

FIG. 4 is a bottom view thereof;

FIG. 5 is a top view thereof;

FIG. 6 is a rear view thereof;

FIG. 7 is a front view thereof;

FIG. 8 is an isometric view of an adhesive bandage dispenser showing a second embodiment of my new design;

FIG. 9 is a right side view thereof;

FIG. 10 is a left side view thereof;

FIG. 11 is a bottom view thereof;

FIG. 12 is a top view thereof;

FIG. 13 is a rear view thereof; and,

FIG. 14 is a front view thereof.

The broken lines depict an adhesive bandage being dispensed from the article and form no part of the design.
